UNITED STATES PATENT OFFICE.

SILAS ANSON, OF BELLEVUE, MICHIGAN.

BARREL-HEATER.

SPECIFICATION forming part of Letters Patent No. 271,763, dated February 6, 1883.

Application filed November 20, 1882. (No model.)

To all whom it may concern:

Be it known that I, SILAS ANSON, of Bellevue, in the county of Eaton and State of Michigan, have invented a new and Improved Barrel-Heater, of which the following is a full, clear, and exact description.

My invention consists of a platform or base of suitable size and form for setting barrels on it to be heated, with a fire-grate in the center 10 and a fire pot or box located on it, and having a suitable chimney or flue, the object being to provide means for heating and shrinking barrels without burning them, all as hereinafter fully described.

Reference is to be had to the accompanying drawings, forming part of this specification, in which similar letters of reference indicate corresponding parts in all the figures.

Figure 1 is a sectional elevation of my improved barrel-heater and a barrel placed thereon to be heated. Fig. 2 is a plan view of the base or platform. Fig. 3 is a plan view of the grate and collar. Fig. 4 is a side elevation of Fig. 3; and Fig. 5 is a perspective view of parts of the fire-pot and flue, showing the manner of connecting them.

a represents a base-plate platform, of sheet or cast iron, as preferred, sufficiently large for the largest size of barrels *k* to be set upright on it, 30 and being mounted on any approved supports, *b*, to elevate it sufficiently above the ground to maintain a fire on a grate, *c*, to be placed over the central opening, *d*, for the purpose.

e represents the fire-pot, to be set upright 35 on the fire-grate; *f*, the flue to the fire-pot; and *g* represents the collar to the grate, said collar supporting the fire-pot over the said opening *d*, and closing the margin of the opening, that is larger than the bottom of the fire-pot.

40 As shown in the drawings, the grate-supporting collar *g* is formed of an annular base having an upwardly and inwardly inclined head-flange to fit the fire-pot, which head-flange may have larger or smaller apertures to receive fire-pots of varying size on the grate-bars *c*, which are firmly secured to the base of the collar. A single grate-collar, suitable for a large fire-pot, may be provided, and smaller fire-pots used therewith on the grate for smaller 45 barrels, in which case the grate-collar may be permanently secured to the base-plate *a* in the

position shown in Fig. 1; but by making the grate-collar removable a number of them, varying in size to fit different fire-pots, may be used interchangeably, whereby the one base 55 *a* *b* may be used for barrels, casks, and kegs of any size. The flue is removably connected to the top of the fire-pot by standards or legs *h* and brackets *i*, so that its base is elevated above the top of the fire-pot to provide an 60 open space, *j*, through which the heat may act directly upon the barrel for a certain distance along the center, care being taken to limit said opening to a size through which the fire will not burn the barrel to any material extent. 65

The flue *f* is smaller at the base than the top of the fire-pot, so that the latter may be conveniently fed with fuel, either through the top of the flue or the space *j* between the flue and the fire-pot.

It will be seen that with this improved heater the barrels can be heated more uniformly and thoroughly than by the common method without burning them, and more substantially, or lasting fuel may be used, requiring less time 75 and labor of attending to the fires. In some cases I shall use a straight fire-pot, instead of the tapered one, *e*, shown in the drawings.

Having thus described my invention, what I claim as new, and desire to secure by Letters 80 Patent, is—

1. In a barrel-heater, the combination, with the fire-pot, of the grate *c*, having the inwardly projecting annular collar *g*, said fire-pot resting upon the grate-bars, and the upper 85 edge of the collar fitting against the outer side of the fire-pot, substantially as and for the purpose set forth.

2. The combination, in a barrel-heater, of a platform, *a*, fire-grate *c*, fire-pot *e*, and flue *f*, 90 said flue and fire-pot being arranged with a space, *j*, between them, and the flue being smaller at the space than the fire-pot, substantially as shown and described.

3. The combination, in a barrel-heater, of a 95 platform, *a*, fire-grate *c*, collar *g*, fire-pot *e*, and flue *f*, said fire-grate and collar and fire-pot being removable, substantially as described.

SILAS ANSON.
